UNITED STATES PATENT OFFICE.

EARL S. SNYDER, OF COMPTON, CALIFORNIA.

ARCH RESTORER.

Application filed May 11, 1927. Serial No. 190,560.

My present invention is an improvement of the orthopedic arch restorer which is set forth in my Patent No. 1,573,652, dated Feb. 16, 1926.

5 The broad object of the invention is to provide in a single instrument a simple, effective and practical means for treating the foot not only for some special defect or ailment or pain, but also to provide a device 10 which can be used progressively in the treatment of any case so that from the aggravated condition at start of use of the instrument the foot can be corrected, built up and finally restored to a normal condition for the 15 particular case being treated.

An object is to provide a device having means designed to be utilized in the treatment of all of the bones, tissues, tendons and muscles by peculiar reaction surfaces 20 effective, by selection of the proper part of the instrument, to actively work the intricate bones and joints as may be necessary according to the case. For instance the present restorer has means for working on the 25 large transverse and longitudinal arches; for intimately effecting action of the bones and joints of the metatarsus, and of the phalanges. It provides means for a gradual and easy reaction and also has means for sharp 30 or acute angular arching, and means for a compacting or narrowing transverse compression.

A further object is to provide a rolling arch restorer incorporating means for supplying external heat to the foot while it is being massaged and, further, to provide for subjecting the foot to magnetic influence.

Additional objects, advantages and features will be made manifest in the ensuing 40 specification of the herewith illustrated embodiment; it being understood that modifications, variations and adaptations may be resorted to within the spirit, scope and principle of the invention as it is more directly 45 claimed hereinafter.

Figure 1 is an elevation of the restorer, mounted on guides.

Figure 2 is a view of one end.

Figure 3 is a cross-section of the restorer.

50 Figure 4 is a view of the wire inlet end of the device.

Figure 5 is a sectional detail of the mount-

ing of a coil core in the chamber of the restorer.

Figure 6 is a sectional view of the feed 55 wire inlet and core mount, in the restorer.

Figure 7 is an end view of the core or spool.

The instrument in the present form includes a hollow roller having at each end a 60 tracking rim 2 one end being rounded at 3 and the other being bevelled at 4 so as to form easy running guide ends to engage the guide flanges 5 of a track device 6. This may consist of any suitable structure, as connected angle pieces here shown or otherwise. 65

The end rims 2 flank a body portion which is of cylindrical form and has variously spaced peripheral beads, straight portions and a wide crowned part.

70 The crowned part 10 has a surface 11 of convex curved outline and at its high line merges into a shorter curved surface 12, of less radius, which ends in a curved bottom valley 13. Next to this valley is a large 75 bead 14 presenting a convex face 15 which is of greater diameter than the crown 10. The curve of the large bead 14 merges smoothly into the near side of the valley 13.

Next to the bead 14 is a short, straight 80 cylinder 16 ending in a high, sharp side ridge or bead 17, which is of about one-half of the width of the major bead 14 and about equally as high.

Beyond the sharp bead 17 is a straight 85 cylinder part 18. Next to this is a medium bead 19, that is, a bead not as sharp as bead 17 but sharper than the bead 14.

A characteristic feature of the present 90 restorer is a series of small closely grouped ribs or beads 20 lying between the medium bead 19 and one end rim 2.

The beads 14, 17 and 19 are of about uniform diameter (and less than the rims 2) but the ribs 20 are smaller in diameter and 95 lie depressed between the bead 19 and the near rim 2.

The ribs 20 are spaced by round bottom 100 valleys 21 which increase in width toward the bead 19. The ribs 20 and valleys 21 form close corrugations around the roller.

Many cases of foot trouble show benefit when subjected to warm applications of different sorts. My instant invention is de-

signed to afford means for effectively working the foot structure and at the same time supply external heat and, additionally, to provide magnetic fluxes in proximity to the 5 treated foot.

To that end the chamber of the roller has an entrance end to receive a coil C of magnet wire on a core or spool S which has a spacing flange F on one end and at its other 10 a set of lugs L suitably fastened in the recessed, open end of the roller, which is closed by a name place or cap 25. The cap has suitable means 26 through which the feed wires W of the coil pass, for desired connection.

The use of the restorer will of course be varied according to the particular case to be treated, as determined by the ailment.

The foot is placed on the large crown part 20 and is then pushed back and forth to the extremes without rolling off. Rolling with a light pressure will indicate at what zone of the foot the soreness or misalignment is most serious. Treatment is continued with 25 gradual increase of pressure of the foot; the periods of treatment varying with the case.

In action upon the heavier bones such as the cuneiforms, the cuboid, the scaphoid and the astragalus and os calcis considerable 30 more pressure may be exerted than upon the metatarsus and these will bear more pressure than the phalanges.

In all cases the pressure will be determined by the sensitiveness of the structure 35 and as this is gradually worked out by regular periodic treatments the pressure is gradually increased as the affected part is restored to a normal, natural form and pain-free state. The affected part is first treated 40 to action on the arch or crowned part 10 to make the foot supple and to locate the source of ailment and restore the misalignment as related to the whole foot. After this the 45 foot is shifted to the corrugated part 20 which, by reason of its numerous ridges and valleys, will act to individually reach and affect the longitudinal metatarsals and also the sections of the toes. If any of these is misaligned or unduly raised or lowered the 50 corrugated body will disclose the location and the foot can be rolled either straight on

the beads or can be angled obliquely so that a rapid and multitudinous vibration can be set up in one stroke of the foot.

As the foot is strengthened and its pliability is increased a cross-arch shaping is secured by placing the foot on the major ridge 14 and rolling to and fro. This causes the transverse metatarsal arch to bow upward a degree which will depend on the pressure 60 and reaction. In this action one side of the foot can be rested on the cylinder 16, as when it is desired to specially treat the inner longitudinal arch.

The cylinder 18 is brought into use to 65 laterally compress the spread sides of the foot and reduce the transverse arch.

The beads 17 and 19 are used in reactions on zones which do not seem to respond, for some reason, to other elements of 70 the device. Heat and magnetic action may be obtained at will by energizing the coil C while treating the foot.

The restorer may be made in different sizes and of adaptable material in its several parts.

What is claimed is:

1. A rollable, arch restoring instrument having a series of differential bead portions for the progressive treatment of the foot by 80 reaction thereon when rolled under foot pressure and including a wide crown part and a bead part of greater diameter than the crown part and both merging into a concave valley.

2. An arch restoring instrument comprising a rollable body having tracking end flanges and having therebetween differential beads in a group of three, and cylindrical parts lying at the sides of the intermediate 90 bead and being of different length; the intermediate bead being the smaller of the group.

3. A rollable arch device, for progressive treatment of the foot, including a roller 95 having a group of spaced beads of substantially uniform diameter and an adjacent bead of greater diameter and width and which is spaced by a valley wider than those spacing the beads of the group.
